DRAFT RIGGING

Donald S. Barrows, Rochester, N. Y., assignor to
The Symington Company, Rochester, N. Y., a
corporation of Maryland

Application January 31, 1931, Serial No. 512,664

14 Claims. (Cl. 213—69)

This invention relates to draft rigging, and more particularly to a coupler adapted for connection to a yoke by means of an upright key providing for horizontal, and, if desired, vertical, angling therebetween.

The principal object of my invention, generally considered, is to provide a simple and economically manufactured coupler adapted to be connected to a vertical yoke, or one with vertically spaced slotted portions, by means of a vertical or upright key passing through the slots in said spaced portions, shims or bearing blocks being associated with one another, and the key and coupler, so that said coupler may angle horizontally with respect to the yoke under the action of both draft and buffing forces, and also vertically, if desired, without any appreciable wear on the connecting key.

Another object of the invention consists in providing the shank or stem member of a coupler with a vertical slot or aperture therethrough, the end wall of said shank rearwardly of said aperture having a curved rear surface which may either be cylindrical about a vertical axis, or spherical, and a front or inner surface preferably curved about a horizontal axis and preferably toroidal, said rear wall being formed with a longitudinal aperture preferably receiving a loop on a bearing block or outer shim, the face of said shim engaging the coupler stem being correspondingly curved and adapted to angle with respect thereto, said forwardly extending loop normally embracing a key adapted to connect the coupler to an associated yoke, and an inner shim disposed between the rear edge of said key and the front face of said rear wall whereby the desired angling movements of the coupler with respect to the yoke are permitted.

Other objects and advantages of the invention relating to the particular arrangement and construction of the various parts will become apparent as the description proceeds.

Referring to the drawings illustrating my invention, the scope whereof is defined by the appended claims:—

Figure 1 is a horizontal sectional view on the line 1—1 of Fig. 2, showing one embodiment of my improved coupler or drawbar with the associated shims or bearing blocks and connecting key in place.

Figure 2 is a longitudinal vertical section on the line 2—2 of Fig. 1, looking in the direction of the arrows, the connecting draft key being shown in side elevation, parts of the associated

yoke and railway vehicle with which used being illustrated.

Figure 3 is a fragmentary sectional view on the line 3—3 of Fig. 2, looking in the direction of the arrows.

Figures 4 and 5 are fragmentary views corresponding, respectively, to Figs. 1 and 2, but showing a modification.

Figures 6 and 7 are fragmentary views corresponding, respectively, to Figs. 1 and 2, but showing another modification.

Figures 8 and 9 are fragmentary views corresponding, respectively, to Figs. 1 and 2, but showing a still further modification.

Figure 10 is a fragmentary view corresponding to Fig. 9, but showing a modification thereof.

Referring to the drawings in detail, like parts being designated by like reference characters, and first considering the embodiment of my invention shown in Figs. 1, 2 and 3, there is shown a coupler 1 having a stem or drawbar 2 provided with a transverse or vertical slot 3, leaving a rear wall 4. The rear surface 5 of the wall 4, in the present embodiment, is shown cylindrical about a vertical axis, and is provided with a longitudinal aperture 6 receiving a forwardly extending tongue or loop 7 on a bearing block or outer shim 8. The shim 8 is formed with a concave cylindrical front face 9 fitting the convex rear surface 5 on the drawbar 2 so that horizontal angling of said drawbar with respect to said shim is permitted, the clearance between the tongue 7 and the aperture 6 and interior cavity 10 in the coupler stem or drawbar being sufficient to permit a reasonable amount of such angling.

The front or inner face 11 of the rear wall 4 of the coupler stem is curved about a horizontal axis, and, in the present embodiment, is shown toroidal, with its major radius extending from a normally horizontal axis, although, I do not wish to be limited to this showing. An inner shim, key seat member, or bearing block 12, desirably closely fitting, between the side walls of the stem 2 defining the receiving pocket, with a correspondingly formed rear face 13 fitting the front face or surface of the wall 4 of said stem, and a preferably vertically straight, concavely curved front face 13' fitting the convex or cylindrical rear face or edge of a key 14, is disposed between said inner wall 4 of the stem 2 and the vertical or upright key 14 which normally serves to connect the coupler stem or drawbar 2 with an associated yoke 15 which, in the present embodiment, is shown as of the vertical type, comprising vertically spaced arms 16,

the forward portions of which are provided with registering slots 17 receiving the upper and lower ends of the key 14. In order to support the key 14, the lower end of said key is desirably provided with a notched head 18 riding on a pin or horizontal supporting element 19, the ends of which are supported on ledges 20 and 21 depending from the lower arm 16 of the yoke 15, transverse retaining means 22 being desirably provided to prevent loss or undesired removal of the pin 19.

The parts of the assembled coupler and yoke are desirably held in place by having the inner shim or bearing block 12 interlocked with the 15 forwardly extending loop 7 by having a rearwardly opening notch 23 fitting the rearmost portion of the loop 7, as shown most clearly in Fig. 2, and forming shoulders on the shim above and below the rear portion of the loop to prevent 20 undesired displacement of the shim, with sufficient clearance to permit the desired angling between the parts. The loop 7 provides a slot 24 registering with the slots 3 and 17 in the coupler and yoke, respectively, for receiving the key 25 14 which connects the parts, the key 14 locking the rear shim or block 6 in place by passing through the slot 24 therein and holding the front or inner shim 12 in interlocked relation with the loop 7, as shown most clearly in Figure 2. The 30 slot 3 in the coupler shank 2 preferably flares forwardly or has the side walls thereof diverging toward the front end, as shown most clearly in Figure 1, so that the coupler may angle horizontally the desired amount with respect to the 35 key. The diverging sides of the slot 3 are preferably tangent to the curved front face of the inner or front shim 12, or the curved rear edge of the key 14, when in place, so that relative angling between the coupler and key is permitted 40 without any excess in the size of the coupler slot.

In Figure 2 the coupler and yoke are shown assembled between the sills 25 of an associated railway vehicle, the front ends of which have connected thereto the striking casting 26 through 45 which the coupler stem 2 extends. The yoke, only the forward portion of which is shown, preferably has the rearmost portion of normal construction embracing an associated follower and/or cushioning mechanism 27, diagrammatically indicated by dot-and-dash lines. Under 50 the action of draft forces, the coupler, through its keyed connection with the yoke, pulls the rearward portion of the cushioning mechanism forwardly, the forward portion being stopped in 55 any desired manner, as by means of the usual front draft lugs (not shown). Horizontal angling of the coupler with respect to the yoke is permitted on draft about the rear edge of the key 14, the inner shim 12 angling or swiveling 60 about said rear edge. Vertical or up-and-down movements of the coupler with respect to the yoke take place about the vertically curved rear face or edge of the shim 12 because of the vertical curvature or toroidal shape of said rear edge and the engaging surface at the front of the rear wall 4 of the coupler stem.

Under the action of buffing forces, the coupler shims and associated vertical key move rearwardly with respect to the yoke 15, said key 70 sliding in the elongated slots 17 in the yoke arms, pushing the front follower and/or cushioning mechanism rearwardly, and compressing the same against rear draft lugs or other backstop means (not shown). Horizontal angling of the 75 coupler on buff takes place about the rearward

portion of the key 14 as a center, the cylindrical rear face 5 of the coupler stem swivelling on the curved front face 9 of the outer shim or bearing block 8. No such provision in this embodiment is made for vertical angling on buff, such angling being possible, however, by canting of the bearing block or rear shim 8 on the front face of the front follower or cushioning mechanism 27.

In the embodiment disclosed, and with particular reference to Figure 1, it will be seen that the loop 7 on the rear bearing block or shim 8 has the rearward portion widened to receive the front or inner shim 12, as indicated at 28, the shoulders 29 formed where the widening takes place being normally spaced from the front edge of the shim 12 to permit disengagement of the shim after withdrawal of the key 14, said disengagement being effected by moving the shim forwardly until the notched portion 23 disengages from the rear portion of the loop 7. It will be seen that one of the characteristics of the construction just described is that the rear surface of the end wall is curved horizontally or cylindrically, while the front surface is curved vertically.

Referring now to the embodiment of my invention illustrated in Figures 4 and 5, a construction is there disclosed which is substantially identical with that of the first embodiment, except that the 30 engaging surfaces 5a on the rear wall 4a of the coupler stem or drawbar 2a and the front face 9a on the associated rear shim or bearing block 8a are spherical rather than cylindrical, so that when the coupler is subjected to buffing forces, 35 vertical as well as horizontal angling may take place between the coupler stem and the rear or outer bearing block or shim 8a without canting or tilting of said shim. As in the previous embodiment, the shim 8a is provided with a forwardly 40 extending, preferably integral horizontal loop 7a normally registering with the coupler slot 3a and corresponding slots in the yoke (not shown), the front or inner shim 12a being provided with a notch 23a receiving the rearward portion of the 45 loop 7a for interlocking the shim in place, said shim being removable after withdrawal of the key 14a because of the clearance 28a provided between the shoulders 29a on the loops 7a and the front of the shim 4a. Except as specifically described in 50 connection with the present embodiment, the same may correspond with that of the first embodiment.

Referring now to the embodiment of my invention illustrated in Figures 6 and 7, a construction is there disclosed which may be substantially identical with that of Figures 4 and 5, except that the key 14b connecting the coupler stem 2b and the yoke 15b is narrower and thicker than the key of the previous embodiments, the slots in said 60 coupler and yoke and in the tongue 7b on the rear shim 8b, and the curvature of the front face of the inner shim 12b being correspondingly changed in shape or curvature, but the construction being otherwise substantially identical.

Referring now to the embodiment of my invention illustrated in Figures 8 and 9, a construction is there disclosed which is substantially identical with that of Figures 1 and 2, except that the key is narrower and thicker, and instead of having 70 the sides parallel, said sides flare or diverge forwardly, providing a key 14c substantially wedge-shaped in horizontal section. The construction is otherwise identical, except for the changes in the shape of the loop 7c formed on the block or shim 75

8^c for connecting said shim to the coupler stem 2^c and interlockingly holding the inner shim 12^c in place. The loop 7^c of the present embodiment, is as wide at the forward portion as where it joins 5 the block proper, and is not reduced in width at its forward portion to provide shoulders, as in the first embodiment, because the increased forward width of the key 14^c is as great as the width of the key embracing portions of the shim 12^c. The 10 advantage of having the connecting key 14^c wedge-shaped in section is that the inner shim may be made to correspond with the shim of Figures 1, 2 and 3, that is, the figures in which a thin and relatively wide key is used, while at the 15 same time maintaining substantially the advantages of the relatively thick and narrow key of Figures 6 and 7.

Referring now to the embodiment of my invention illustrated in Figure 10, a construction is 20 there disclosed which is identical with that of Figures 8 and 9 except that the front face of the rear or outer shim 8^d which is connected to the coupler stem 2^d by the vertical wedge-shaped key 14^d passing through a slot in the loop or forward 25 projection 7^d is spherical rather than cylindrical, and the rear surface of the coupler stem 2^d is correspondingly curved.

From the foregoing disclosure, it will be seen 30 that I have devised a coupler normally connected to an associated yoke by means of a vertical key permitting transverse or horizontal angling and associated with shims permitting vertical angling.

Although preferred embodiments of my invention 35 have been illustrated, it will be understood that modifications may be made within the spirit and scope of the appended claims.

I claim:—

1. In railway draft rigging, in combination with 40 a coupler stem having a rearwardly opening pocket and a spherical bearing face on the rear end thereof, a vertical yoke, cushioning mechanism embraced by said yoke and disposed rearwardly of the coupler stem, an outer shim with a front spherically concave face fitting the spherical 45 rear end of the coupler stem and a tongue received in said stem pocket, said coupler and yoke having normally registering slots, a vertical key passing through said slots, an inner shim disposed between the rear edges of said key and coupler slot, 50 said inner shim having a convex rear surface nesting with a concave surface in the stem for vertical angling and a concave forward face fitting the rear edge of said key, the outer shim tongue being also formed with a slot normally registering with 55 the coupler slot and receiving said key for holding said shim in place, said inner shim being formed with a notch engaging a portion of said tongue for interlocking the parts together, and means connected to said yoke for supporting said key.

2. In railway draft rigging, in combination with 60 a coupler stem having a rearwardly opening pocket, a convex spherical bearing face on the rear end of said stem, a vertical yoke, cushioning mechanism embraced by said yoke and 65 disposed rearwardly of the stem, an outer shim with a front spherically concave face fitting the spherical rear end of the coupler stem, and having a tongue received in said stem pocket, said coupler and yoke having normally registering 70 slots, a vertical key passing through said slots, an inner shim disposed between the rear edge of said key and coupler slot, said inner shim having a convex rear surface fitting a concave 75 surface in the stem for vertical angling, a forward face engaging the rear edge of said key,

and a portion of said inner shim providing a shoulder lying above said tongue to prevent undesired shim displacement, the outer shim tongue having a slot normally registering with the coupler slot and receiving said key and inner shim for holding the parts in place. 3

3. In railway draft rigging, in combination with a coupler stem having a rearwardly opening pocket and a convexly curved bearing face on the rear end thereof, a vertical yoke, cushioning mechanism embraced by said yoke and disposed rearwardly of the coupler stem, an outer shim with a front concavely curved face fitting the rear end of the coupler stem and a slotted tongue received in said stem pocket, said coupler and yoke having slots normally registering with the tongue slot, a vertical key with a vertically straight, horizontally rounded, rear edge portion, and passing through all of said slots, an inner shim disposed in said coupler and tongue 20 slots rearwardly of said key, said inner shim having a vertically curved surface fitting a correspondingly curved surface on the stem for vertical angling only, and a vertically straight forward face nesting with the rear edge portion 25 of said key to allow for horizontal angling only.

4. A car coupler comprising a shank having a rear end wall and a transversely extending slot in advance thereof, said rear wall having curved rear and forward surfaces and being apertured, 30 a bearing block having a curved forward face cooperating with said curved rear surface, a shim positioned in said slot and having a curved rear face cooperating with said curved forward surface of the rear wall of the shank member, 35 means extending through the aperture in said wall for connecting said bearing block and shim, said means having a slot registering with the coupler slot and the rear face of said shim being notched to engage said means, and means for 40 holding said bearing block and shim in assembled relation with respect to said shank.

5. A coupler comprising a shank having a curved rear end and a curved interior surface in advance thereof and formed with a transversely extending slot, a key seat member having a curved rear face corresponding to and engaging said interior surface of the shank, a bearing block adapted to engage the forward portion of associated cushioning mechanism and 45 having its forward face curved for cooperating with the curved rear end of the shank member, means extending forwardly from said bearing block into said shank for connecting said bearing block thereto, said means having shouldered 50 portions overlying the forward edge of the key seat member but forwardly spaced therefrom to permit relative longitudinal movement therebetween for removal of said key seat member from the shank and means for retaining the key seat 55 member and bearing block in position.

6. A coupler comprising a shank formed at its rear end with a curved exterior surface and having a curved interior surface in advance thereof, said shank being transversely slotted 65 and formed with a rearwardly opening recess communicating with said slot, a bearing block adapted to engage associated cushioning mechanism and having a curved forward face for cooperating with the curved exterior surface of 70 the shank, a shim positioned in said slot and having a curved rear face for cooperating with the curved interior surface of the shank, a loop member extending forwardly from said bearing block through said recess and embracing said 75

- shim, the rear face of said shim being notched to interlock with the corresponding portion of the loop member, and means acting to retain the bearing block and shim in assembled relation 5 with respect to said shank.
7. A coupler comprising a shank formed at its rear end with a curved exterior surface and having in advance thereof a curved interior surface, a bearing block adapted to engage the forward 10 portion of associated cushioning mechanism and having a curved forward face for cooperating with said exterior surface of the shank, a shim having a curved rear face for cooperating with said curved interior surface of the shank, a loop 15 member for connecting the bearing block to the shank, said loop member having spaced portions between which the shim extends, said shim being formed with a notch in the rear portion interlocking with the loop member, said loop 20 member having shoulders normally forwardly spaced with respect to said shim for permitting forward movement of said shim for disengagement of the notch portion with respect to said loop member, and means normally retaining the bearing block and shim assembled in proper 25 relation with respect to the shank.
8. In railway draft rigging, in combination with a coupler stem having a rearwardly opening pocket and a curved bearing face at the rear 30 end thereof, a vertical yoke, cushioning mechanism embraced by said yoke and disposed rearwardly of the coupler stem, an outer shim with a front curved face fitting the curved rear end of the coupler stem and a tongue received in said 35 pocket, said coupler yoke and tongue having normally registering slots, a vertical key and associated inner shim passing through said slots, the rear surface of the inner shim and the engaged surface of the coupler stem being correspondingly curved to allow angling therebetween, the slots in said yoke being extended rearwardly 40 of the normal position of the key to allow the coupler to move rearwardly independently of the yoke to compress said cushioning mechanism, and means connected to said yoke for supporting 45 said key and preventing loss of said shims, the lower portion of said key engaging said means and slidably therealong with the coupler upon longitudinal movement of said coupler with respect to said yoke.
9. A coupler comprising a shank having a rear 50 end wall and a transversely extending slot in advance thereof adapted to receive a vertical key having a cylindrically curved rear edge portion, and the end portions of which are received in 55 registering slots in an associated yoke, said wall having a rear surface curved cylindrically about a vertical axis and a forward toroidal surface with a major radius having a horizontal axis, a bearing block having a correspondingly curved forward face cooperating with said rear surface, and a key seat member positioned in, and closely fitting between side walls defining, said shank slot and having a forward portion adapted to be 60 engaged by, and curved to correspond with the rear edge portion of, said key and a rear face correspondingly curved and cooperating with said curved forward surface of said rear wall, said bearing block being provided with a forwardly extending portion embracing the key seat member, and said key when in place passing through said forwardly extending portion and holding said bearing block and key seat member in assembled relation with respect to said shank.
- 70 75 10. A coupler comprising a shank having a

rear end wall and a transversely extending slot in advance thereof, said wall having a rear cylindrical surface horizontally curved and a forward toroidal surface vertically curved about its major axis, a bearing block having a correspondingly curved forward face cooperating with said curved rear surface, a key seat member positioned in, and closely fitting between side walls defining, said slot and having a rear face correspondingly curved and cooperating with said curved forward face of said rear wall for vertical angling only with respect thereto, and means comprising a vertical key passing through an extension on said bearing block and coupler shank slot and in engagement with said key seat member for holding said bearing block and key seat member in assembled relation with respect to said shank.

11. A coupler adapted for attachment to a draft yoke or the like comprising a shank having a rear end wall and a transversely extending slot in advance thereof, said rear wall having a rear surface cylindrically curved about normally upright axis and a forward toroidal surface with a major radius having an axis at right angles to the axis of the rear surface, a key seat member positioned in, and closely fitting between side walls defining, said slot, and having a rear face correspondingly curved and engaging the forward surface of said rear wall so that it is adapted to angle only about the major axis of said surface, and a bearing block member adapted to engage the follower of an associated draft gear and having a forward face correspondingly curved for cooperating with the curved rear surface of said rear wall of the shank, so that it is adapted to angle about the axis of said surface, said block having a tongue fitting in an opening in the rear end of said shank and formed with a slot registering with the shank slot for receiving a connecting draft key in pivotal engagement with the front face of said key seat member.

12. A coupler adapted for attachment to a draft yoke or the like, comprising a shank having a rear end wall and a transversely extending slot in advance thereof, adapted to receive a vertical key having a cylindrically curved rear edge portion, said slot having the side walls thereof flared or diverging forwardly to provide for a relatively large amount of angling with respect to said key, said end wall having a rear surface curved cylindrically about a normally vertical axis and a forward toroidal surface with a major radius having a normally horizontal axis, a bearing block having a forward face correspondingly curved and cooperating with said rear surface, and a key seat member positioned in, and closely fitting between, side walls defining said shank slot, and having a forward portion adapted to be engaged by, and curved to correspond with, the rear edge portion of said key, and a rear face correspondingly curved and cooperating with said curved forward surface of said rear wall, said bearing block being provided with means forming a loop and extending from a central portion through said rear end wall of the shank, cooperating with the key seat member and adapted to receive said key, said loop being as wide at its forward portion as where it joins with said block.

13. A coupler adapted for attachment to a draft yoke or the like, comprising a shank having a rear end wall and a transversely extending slot in advance thereof, said slot having side

walls diverging forwardly and adapted to receive a vertical key therebetween, having a cylindrically curved rear edge portion, and allowing for a relatively large amount of angling with respect thereto, said end wall having a rear surface curved cylindrically about a normally vertical axis, and a forward toroidal surface with a major radius having a normally horizontal axis, a bearing block having a forward face correspondingly curved and cooperating with said rear surface, and a key seat member positioned in, and closely fitting between, side walls defining said slot and having a forward portion adapted to be engaged by, and curved to correspond with, the rear edge portion of said key, and a rear face correspondingly curved and cooperating with said curved forward surface of said rear wall, said bearing block being provided with a forwardly extending portion forming a loop passing through the rear end wall of said shank, with the key and key seat member passing therethrough, the key seat member being wider than the engaging portion of said key, said loop being as wide at its forward portion as at its rearward

portion, and said key being integral and having forwardly diverging side surfaces, said key, when in place, holding said bearing block and key seat member in assembled relation with respect to said shank.

14. A coupler with a stem having a rearwardly opening pocket and a convexly curved bearing face on the rear end thereof, an outer shim with a front concavely curved face fitting the rear end of the coupler stem and a tongue received in said stem pocket, said coupler and tongue having normally registering slots adapted to receive a connecting vertical key with a vertically straight, horizontally rounded, rear edge portion, and passing through all of said slots and with its ends adapted for reception in registering yoke slots, an inner shim disposed in said coupler and tongue slots rearwardly of said key, said inner shim having a vertically curved surface fitting a correspondingly curved surface on the stem for vertical angling only, and a vertically straight forward face nesting with the rear edge portion of said key to allow for horizontal angling only.

DONALD S. BARROWS.
